UNITED STATES PATENT OFFICE.

ISAAC A. WESSON, OF WINGO, KENTUCKY.

HORSE-DETACHER.

SPECIFICATION forming part of Letters Patent No. 297,205, dated April 22, 1884.

Application filed January 15, 1884. (No model.)

To all whom it may concern:

Be it known that I, ISAAC A. WESSON, a citizen of the United States, and a resident of Wingo, in the county of Graves and State of Kentucky, have invented certain new and useful Improvements in Horse-Detachers; and I do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of one end of a single-tree provided with my improved horse-detacher. Fig. 2 is a similar view, showing the device in position detaching; and Fig. 3 is a similar view of the several parts separated.

Similar letters of reference indicate corresponding parts in all the figures.

My invention has relation to that class of horse-detachers in which the traces are hooked upon pivoted hooks at the ends of the single-tree; and it consists in the detailed construction and combination of parts of the same, as hereinafter more fully described and claimed.

In the accompanying drawings, the letter A indicates the single-tree, upon the outer end of which a socket, B, fits, having two lips, C, projecting outward from its upper and lower side, and having a bar, D, extending inward from its rear side, which bar is secured to the rear side of the single-tree. The outer ends of the two lips are provided with upwardly and downwardly projecting enlargements E at their outer ends, and a pin, F, passes through the outer ends of the lips. The hook G is pivoted upon this pin, and consists of a T-head, H, the rear horn or arm of which is longer than the front arm, and a bar, I, fitting and bearing against the rear side of the single-tree when the hook is in position, both of which parts project in opposite directions from the central flat portion, J, through which the pivotal pin passes, and which turns upon the same. The inner end of the bar I is slotted transversely, and fits over an eye, K, which projects through the slot, and through which 45 a wire spring-key, L, passes, which secures the bar in position, bearing against the rear

side of the single-tree. The inner end of the bar D forms an enlargement, M, at the end of the bar of the hook, which enlargement is grooved longitudinally at N, and provided with 55 an eye, O, through which the spring-key slides. The spring-key is formed by a piece of spring-wire, having one end, P, doubled and sliding in the eye, passing through the slot in the bar of the hook, whereupon the wire is coiled at 60 Q, and the end, which, together with the doubled end, passes through the eye upon the enlargement, is bent outward at R, to make it bear against the inside of the eye, holding the key in place, and bent at a right angle at its 65 extreme end at S, preventing the key from slipping out of the eye upon the enlargement. A rubber cushion, T, formed by a piece of rubber pipe, or any other elastic material, is secured upon the rear side of the socket-bar 70 D, preventing the hook-bar I from rattling against the socket-bar, and a strap, cord, or chain, U, is attached to the eye or coil of the spring-key, which is attached at its other end to the spring-key of the device upon the other 75 device, and another strap, V, is attached to the center of the former strap, being within reach of the driver, who, by pulling the strap, may withdraw the two keys, allowing the hooks to swing forward, releasing the traces 80 from their hooks.

I am aware that it is not broadly new to have the traces hooked upon pivoted hooks at the ends of the single-tree, having means for releasing the pivoted hooks, and I do not 85 claim such construction, broadly; but

What I claim, and desire to secure by Letters Patent of the United States, is—

1. The combination of the single-tree, the socket having the outwardly-projecting lips 90 having enlargements at their outer ends, and the pivoted hook having means for retaining and releasing it, as and for the purpose shown and set forth.

2. The combination of the single-tree, the 95 socket having outwardly-projecting lips provided with the pivotal pin, and the inwardly-extending socket-bar having the longitudinally-grooved enlargement at its inner end, provided with the eye, the hook having T-head perforated central portion and inwardly-extending hook-bar having a transverse slot 100

at its inner end, the rearwardly-projecting eye passing through the said slot, the elastic cushion, and the spring-key, as and for the purpose shown and set forth.

5. The spring-key having one end doubled, central coil, and outwardly-bent end, in combination with the inner eye, the outer eye, and the slotted hook-bar, as and for the purpose shown and set forth.

In testimony that I claim the foregoing as my to own I have hereunto affixed my signature in presence of two witnesses.

ISAAC A. WESSON.
